DEVICE OF THE KIND COMPRISING AN ELECTRONIC TUBE HAVING A RIBBON-SHAPED BEAM WHICH IS DEFLECTED AND HELD IN DIFFERENT POSITIONS

Klaas Rodenhuis, Eindhoven, Netherlands, assignor to Hartford National Bank and Trust Company, Hartford, Conn., as trustee

Application November 21, 1951, Serial No. 257,512
In the Netherlands November 30, 1950

5 Claims. (Cl. 313—82)

1

The invention relates to devices of the kind comprising an electric discharge tube having a ribbon-shaped beam which can be deflected and held in different positions by current distribution.

With such a device, which may, for example, be used for counting pulses, it is of great importance to be able to read the position of the beam quickly and accurately. For this purpose provision is made of means to render the beam position optically visible, for example, a fluorescent screen, if necessary, in conjunction with means revealing the numerals corresponding to the different positions. It has been suggested to use, for this purpose, surface parts alternating in a given manner or luminescent numerals.

In such devices the beam passes, upon deflection, wholly or in part a plurality of electrodes, inter alia grids. In order to ensure an optimum operation of the device, these grids are arranged in a manner such that the wires or rods extend parallel to the direction of deflection of the beam. In this case there is frequently a limitation in that shadows of the grid wires are visible on the fluorescent screen, which is a source of trouble when reading the position of the beam.

A further difficulty is experienced in that the edges of the luminescent surface parts may be more or less vague instead of being sharp, whilst adjacent parts sometimes may also become luminescent. This also renders the reading of the beam position more difficult. It has been found that this drawback is due to the fact that the edges of the beam portions passing through slots and apertures of different electrodes are frequently not sharply defined, inter alia because the edge electrons, which are deflected too strongly, may strike the screen also at the surface parts corresponding to further beam positions.

According to the invention, the said limitations may be substantially completely obviated, if in a device comprising an electric discharge tube having a ribbon-shaped beam, which can be held in different positions by current division, and which passes in succession, wholly or in part, through a deflection system, a grid which is at low potential or at zero potential and of which the wires extend parallel to the direction of deflection of the beam, through a slotted screen, one or more grids and perforated electrodes, provision being made of means to render the position of the beam optically visible, the partial beam currents formed by the first grid, which is next to the deflection system and which is at low or zero potential, are focussed approxi-

5 mately in the plane of the slotted screen, whilst viewed in the direction of travel of the electrons behind the slotted screen, there is a second grid at low or at zero potential, the wires of which are located in the shadow of those of the first grid, behind which are provided one or more partially perforated electrodes and means to render the position of the beam optically visible, the arrangement being such that the partial beam currents overlap one another in the area of the optical means, so that a sharply defined image of the beam position, which is luminescent throughout its surface, is produced.

10 The grid arranged behind the slotted screen must have such a wire thickness and be at such a distance from the slotted screen that the electron paths behind this grid are spread in a manner such that the maximum uniformity of luminescence of the surface part associated with the given beam position is obtained. The apertures of the anode are preferably covered by gauze of fine mesh. Thus the part of the beam current which flows to the optical means and which must be regarded as lost for the further 15 operation of the device, is reduced and, moreover, since the apparent shadow ratio of gauze is greater for small angles of incidence, the strongly deflected stray electrons and peripheral electrons will be intercepted for the major part, whereas the electrons arriving at right angles at the gauze are allowed to pass for a greater part. Moreover, owing to the gauze, the potential in the apertures becomes substantially equal to that of the plate-shaped portion of the electrode, so that there is no deflection of the passing electrons at the edge of the apertures. The size of the apertures of the anode and the gauze is chosen to be such that less than 20% of the beam current passes through the anode and finds 20 its way to the optical means. If the reproduction is obtained by the luminescence of part of a fluorescent screen applied to the tube wall, the screen must be prevented from taking a negative charge. A bright luminescence requires that the electrons should impinge upon the screen with great velocity. For this purpose the screen must be kept at a higher positive potential. This is furthered by drawing off the secondary electrons from the screen by means of a post-acceleration electrode, so that the screen 25 takes a positive charge. When starting the device, it may, however, occur that the secondary emission is too low at first, so that the screen takes a negative potential. This is avoided by 30 providing a conductive, transparent, layer be-

tween the screen and the substratum, i. e. in this case the glass bulb of the tube and by connecting this layer to a point of high positive potential. The use of such layers in cathode-ray tubes is known per se. In the present case a tin-oxide layer is found to be very suitable; it is conductively connected to a post-acceleration electrode, if any, or otherwise, to a further point of high positive potential.

Instead of comprising a fluorescent screen, the means for rendering the beam position optically visible may, as an alternative, comprise windows in an anode coated with fluorescent material, or the like.

In order to allow a rapid identification of the position of the beam, opaque masks may be applied with advantage to the outer side of the bulb, these masks having transparent numerals, which are arranged exactly in front of the associated luminescent surface parts. Very suitable are masks of celluloid, which is photographically blackened, the numerals being left transparent. This has the advantage that the numerals can be accurately arranged on the luminescent surface parts. Since, owing to inaccuracy of the tube construction, the position of the surface parts cannot always be exactly defined beforehand, the use of separate masks is very advantageous, whilst by replacing the mask the indication of the beam position may be shown by other symbols.

In order that the invention may be readily carried into effect, an example will now be described in detail with reference to the accompanying drawings, in which:

Fig. 1 is a longitudinal sectional view and

Fig. 2 is a cross sectional view of one embodiment of the invention.

Referring to the figures, 1 designates an electron gun, 2 a deflection plate, 3 a grid held at zero potential or at a low positive or negative potential, operating as a collecting grid to suppress secondary emission from the slotted screen 4 to the deflection system and 5 designates a grid which is constructed in a manner similar to the grid 3 and which is arranged in a manner such that its wires are located in the shadow of those of the grid 3. The grids 3 and 4 are preferably arranged in a manner such that the foci of the partial beam currents are located approximately in the plane of the slotted screen 4, since in this case divergences in size and position of the slots exert little influence on the passing beam current. The anode 6, which is connected to the output circuit, has a plurality of apertures which are covered by gauze 7 in a manner such that about 8 to 10% of the current reaching this anode passes through the gauze and reaches the fluorescent screen 9 by way of the post-acceleration anode 8. Between this screen 9 and the tube wall 11 is provided a transparent, conductive tin-oxide layer 10, which is connected through a conductor or a spring 13 to the post-acceleration anode 8. Externally of the tube a mask 12 is clamped to the bulb in a manner such that the numerals provided in the mask are exactly in front of the corresponding luminescent parts of the screen 9. The numeral corresponding to the beam position at a particular instant thus becomes apparently luminescent.

The grid 5 is arranged in a manner such that the partial beam currents overlap one another in part on the fluorescent screen, so that an optimum uniformity of luminescence of the surface is obtained, being free from troublesome

shadows of the grid wires and being sharply defined, since stray electrons and peripheral electrons, which are excessively deflected by the grids 3 and 5, are retained by the gauze 7 of the anode 6. The post-acceleration electrode 8 serves to suck off the secondary electrons from the screen 9, so that the latter takes a positive potential and the electrons impinge upon it with greater velocity. The transparent, conductive oxide layer 10 is connected to the post-acceleration electrode 8 by means of the connection 13. If the layer 10 between the screen 9 and the tube wall 11 and the fluorescent screen 9 itself are sufficiently conductive, the post-acceleration anode 8 may, if desired, be dispensed with.

An example of the construction of the grids 3 and 5 and of the spacings between the various electrodes now follows: The grid has a pitch of 1.72 mms., a wire thickness of $130/\mu$ and is spaced apart in front of the slotted screen at a distance of 1.6 mms. The grid 5 also has a pitch of 1.72 mms. and a wire thickness of $130/\mu$, but it is spaced apart behind the slotted screen 4 at a distance of 1.43 mms. The spacing between the slotted screen 4 and the anode 6 is 4.8 mms. and the spacing between the anode 6 and the post-acceleration electrode is 1.5 mms. The apertures of the anode 6 have a height of two grid apertures and are arranged in staggered position for the various beam positions. The gauze 7 has approximately 100 meshes an inch, i. e. a wire thickness of $160/\mu$ and a pitch of $260/\mu$. The apertures of the post-acceleration electrode 8 are not covered with gauze. At a distance of 1.4 mms. behind the post-acceleration electrode 8 is located the fluorescent layer 9, which is separated from the tube wall 11 by a tin-oxide layer 10. Externally of the tube wall 11 is provided a celluloid mask 12.

The electrodes 3 and 5 are connected to the cathode and the anode 6 is connected to +100 to +250 v., the post-acceleration electrode 8 to +300 v. The slotted screen 4 is connected to 250 v.

Fig. 1 shows the travel of the electrons. The stray electrons and the peripheral electrons 14 are retained by the gauze 7 and consequently, cannot give rise to phantom images and unsharp edges of the luminescent parts.

It is evident that with other voltages and other dimensions of the electrodes the grids must have other corresponding dimensions.

What I claim is:

1. An electric discharge tube adapted to count a succession of pulses comprising an envelope and an electron discharge system within the envelope and comprising an electron gun capable of generating a ribbon-shaped beam, a pair of deflection electrodes positioned to deflect the beam to obtain a given number of positions, a first grid electrode having wires positioned parallel to the direction of deflection of the beam, a first slotted screen electrode having slots positioned perpendicular to the wires of the first grid electrode, a second grid electrode positioned on the side of the first screen electrode remote from the electron gun and having wires positioned in register with and parallel to the wires of the first grid electrode, a second slotted screen electrode having slots positioned in register with the slots of the first screen electrode, a gauze covering over a portion of said second slotted screen electrode, a third slotted electrode having slots positioned in staggered register with the slots of said second screen electrode, and a fluorescent screen on a

portion of the inner wall of the envelope in the path of the electron beam.

2. An electric discharge tube as claimed in claim 1 in which the second slotted screen electrode has slots having a cross-sectional dimension at which together with the gauze covering less than 20% of the beam current is passed by the electrode.

3. An electric discharge tube as claimed in claim 1 in which the third slotted electrode is at 10 a positive potential relative to the electron gun and serves as a post-accelerating anode.

4. An electric discharge tube as claimed in claim 1 in which a transparent, conductive tin oxide layer connected to a source of positive 15

potential is interposed between the fluorescent screen and the inner wall of the envelope.

5. An electric discharge tube as claimed in claim 4 in which the conductive layer is electrically connected to the third slotted electrode.

KLAAS RODENHUIS.
